CANE OR UMBRELLA HANDLE.

No. 20,149.

Patented Sept. 9, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,149, dated September 9, 1890.

Application filed August 1, 1890. Serial No. 360,678. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to 5 know which it pertains to make and use it, reference being had to the accompanying drawing, which forms part of this specification.

My invention relates to an improvement in designs for cane, umbrella, or parasol handles; and it consists in the novel shape and configuration of parts whereby a pleasing and beautiful effect is produced, as will be more fully described hereinafter.

The accompanying photographic illustration represents my invention.

A represents the inner plain end of the handle, having the beads B extending horizontally around it. The outer end of this plain portion is grooved longitudinally and provided with a scalloped or irregular edge C. Around the outer end of this portion A is wrapped a streamer D, which is also made to extend around the outer edge of the curved portion G of the handle, which curved portion has its inner end resting upon the scalloped end, as shown. The lower end of this curved portion is given any ornamental shape that may be desired. The outer end of the curved portion G has an offset, shoulder, or recess formed therein, and in this recess is 30 placed the rounded body I. The curved portion G of the handle forms a bend or hook, and the edge of the streamer forms a scallop or irregular line along the side of the bend or hook, as shown.

Having thus described my invention, I claim—

A design for a cane, parasol, or umbrella handle, substantially as herein shown and described.

In testimony whereof I affix my signature in presence of two witnesses.

ALBERT ROSENSTEIN.
